(57) **CLAIM**

(21) Appl. No.: **29/124,951**

The ornamental design for a performance measuring module
and portion of a shoe upper, as shown and described.

(22) Filed: **Jun. 15, 2000**

DESCRIPTION

(51) LOC (7) Cl. **10-04**

FIG. 1 is a left side elevational view of a performance measuring module
and portion of a shoe upper showing our
new design;

(52) U.S. Cl. **D10/70**

FIG. 2 is a right side elevational view thereof;

(58) Field of Search D10/70, 97; D2/976;

FIG. 3 is a top plan view thereof;
FIG. 4 is a front elevational view thereof; and,
FIG. 5 is a rear elevational view thereof.

235/105; 340/323 R; 371/15, 24.2

The broken line showing of a shoe tongue in FIGS. 1-5 is
environmental and forms no part of the claimed design.
